TOY GUN FOR PROJECTING AEROPLANES

Filed Oct. 2, 1934

UNITED STATES PATENT OFFICE

2,029,036

TOY GUN FOR PROJECTING AEROPLANES

William J. Rottner, Brooklyn, N. Y.

Application October 2, 1934, Serial No. 746,488

4 Claims. (Cl. 124—12)

This invention relates to new and useful improvements in a toy gun for projecting airplanes.

The invention has for an object the construction of a device as mentioned which is characterized by an arrangement wherein a pair of flanges are disposed upon the sides of a longitudinal opening along the barrel of a toy gun adapted to project airplanes in such a manner that they act as tracks for guiding the plane.

Still further, the invention also proposes to so arrange the pair of flanges to be at an inclination relative to the barrel of the gun so as to project the plane upwards into the air.

Still further the invention also contemplates an arrangement wherein the pair of flanges are formed from the material of the barrel of the gun continued from the sides of the longitudinal opening.

Still further, the invention also contemplates an arrangement wherein a pair of flanges are adjustably arranged so as to be capable of adjustments in various tilted positions to control the discharging angle of the toy airplane.

Still further the invention contemplates the provision of front sectional pieces upon the flanges adapted to be selectively adjusted for controlling the discharging of the plane.

Another object of the invention is the construction of a device as mentioned which is simple and durable and which can be manufactured and sold at reasonable cost.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:—

Fig. 1 is a perspective view of a toy gun for projecting a toy airplane, and a toy airplane in position on the gun.

Fig. 2 is a longitudinal sectional view of a gun similar to the one shown in Fig. 1 but constructed according to a modification of the invention.

Fig. 3 is a side elevational view of the gun shown in Fig. 2 but illustrating it in a bent position in which the gun is being loaded.

Fig. 4 is an elevational view looking in the direction of line 4—4 of Fig. 2.

Fig. 5 is a transverse sectional view taken on the line 5—5 of Fig. 2.

Fig. 6 is a fragmentary plan view looking in the direction of the line 6—6 of Fig. 2.

Fig. 7 is a perspective view of a device con-

structed according to another embodiment of this invention.

The device, according to this invention, includes a gun stock 10 pivotally connected by a bolt 11 with a gun barrel 12. A plunger 13 is slidably mounted in the gun barrel. A spring 14 is attached at one end upon a transverse rivet 15 extended through the gun barrel, and at the other end connects with the plunger 13 so as to normally urge the plunger forwards from a retracted position when the gun is loaded. A trigger 16 is pivotally mounted by a bolt upon the inner end of the gun barrel 12. This trigger is adapted to hold the plunger 13 in its rear loaded position.

A rod 18 is rigidly attached axially on the plunger and extends rearwards through the barrel. A collar 19 is fixed on the rear end of the rod 18 and is adapted to be engaged by the catch end 16^a of the trigger 16. A coaxial spring 20 is mounted upon the pivot 17 and acts between the trigger and the gun barrel for normally urging the catch end 16^a into operative position. The upper edge of the catch end 16^a has an inclined portion to normally engage the collar 19 and be depressed by the collar when the collar is moved rearwards to the loaded position of the gun. An element 21 is pivotally mounted at its rear end 22, upon the gun stock and extends into the barrel 12 and is formed with a slot 21' engaging over a portion of the collar 19. The gun stock may be bent relative to the barrel to a position as shown in Fig. 3, to cause the element 21 to move the plunger 13 into the loaded position.

Fig. 2 illustrates the gun in its loaded position. A peg 24 projects from the plunger 13 and engages into a longitudinal opening 25 in the gun barrel. A toy airplane 26 has a depending peg 27 (shown by the dot and dash lines in Fig. 2) which is adapted to be engaged by the peg 24 for propelling the toy airplane frontwards when the gun is discharged.

The material of the gun barrel 12 is extended upwards in parallel portions, which parallel portions define the sides of the opening 25. These parallel portions terminate in outward directed flanges 28 forming a track upon which the airplane rests. The flanges are arranged at an inclination from the front to the rear so as to be capable of projecting the airplane upwards or downwards depending merely upon design, that is, the tilt of the track. A projecting portion 29 from a portion of the barrel is adapted to engage in a receiving niche 30 upon the gun stock so

that the barrel and stock may be frictionally held in aligned position as shown in Figs. 1 and 2.

The operation of the device consists in loading the gun by bending the stock portion 10 relative to the barrel portion 12 to a position as illustrated in Fig. 3. When the gun is loaded the airplane may be placed in position upon the top of the gun and then the trigger 16 may be drawn to release the collar 19 so that the spring 14 moves the plunger 13 forwards. The motion of the plunger is transmitted by the peg 24 to shoot the toy airplane forwards. The toy airplane will be guided by the track 28 and the openings 24 until such time that it leaves the gun.

In Fig. 2 a modification of the invention has been disclosed wherein the barrel 12 is formed with a longitudinal opening 25^a associated with tracks 28^a. These tracks are formed by angle irons, separate from the material of the barrel 20 and having vertical and horizontal arms. The horizontal arms are arranged at the top to form supports for the airplane. The vertical arms are pivotally mounted intermediate of their ends by screws 30 mounted through lugs 31 projecting 25 from the edges of the openings 25^a of the barrel. Clamp nuts 32 are arranged on the bolts 30 in such a fashion that the tracks 28^a may be held in various inclined positions. With this arrangement it is possible to direct toy airplane upwards 30 at any desired angle, or downwards.

The angle members 28^a are formed with front sections 28^b which are pivotally connected with the rear sections by bolts 32. Wing nuts 33 engage upon the bolts and are arranged to be 35 capable of holding the front sections at desired relative angles to the rear sections. The front sections 28^b are shown formed with quite broad vertical arms so as to extend into the opening 25^a to guide motion of the flanges when they are adjusted.

A feature of the arrangement lies in the fact that the front sections 28^b may be adjusted at different inclinations (always directed upwards) to the rear sections so that, for example, the toy 45 airplane may first be projected along the flanges 28^a and then be smartly directed upwards when engaging over the flanges 28^b.

In Fig. 7 another embodiment of the invention has been disclosed which is identical to the 50 form shown in Fig. 1, except for the fact that a string 35 is attached at one end upon the toy airplane and at the other end upon the gun so that while the airplane may be discharged into the air, it cannot be lost since it is attached or connected by the string to the gun.

While I have illustrated and described the preferred embodiments of my invention, it is to be understood that I do not limit myself to the precise constructions herein disclosed and the right 60 is reserved to all changes and modifications coming within the scope of the invention as defined in the appended claims.

Having thus described my invention, what I claim as new, and desire to secure by United States 65 Letters Patent is:—

1. A device of the class described, comprising a gun stock pivotally connected with a gun barrel, a plunger in the barrel, a spring urging said plunger forwards, a trigger on the barrel adapted to hold the plunger in a rear position in which the gun is loaded, an element pivotally mounted on the gun stock and associated with the plunger and adapted to draw the plunger rearwards when the gun is bent at the junction of the gun stock and barrel, said barrel being 70

formed with a longitudinal top opening, a pin on the plunger engaging in said opening and coactable with a pin projecting from a toy airplane to propel the airplane as the plunger moves forward, and a pair of flanges on the sides of said opening forming tracks for guiding said airplane, said pair of flanges being pivotally mounted intermediate of their ends and adapted to assume various adjusted tilted positions for projecting the toy airplane at various desired angles. 10

2. A device of the class described, comprising a gun stock pivotally connected with a gun barrel, a plunger in the barrel, a spring urging said plunger forward, a trigger on the barrel adapted to hold the plunger in a rear position in which the gun is loaded, an element pivotally mounted on the gun stock and associated with the plunger and adapted to draw the plunger rearward when the gun is bent at the junction of the gun stock and barrel, said barrel being formed with a longitudinal top opening, a pin on the plunger engaging in said opening and coactable with a pin projecting from a toy airplane to propel the airplane as the plunger moves forward, and a pair of flanges on the sides of said opening forming 20 tracks for guiding said airplane, said pair of flanges being pivotally mounted intermediate of their ends and adapted to assume various adjusted tilted positions for projecting the toy airplane at various desired angles, and clamp screws 25 for holding said flanges in fixed adjusted positions. 30

3. A device of the class described, comprising a gun stock pivotally connected with a gun barrel, a plunger in the barrel, a spring urging said plunger forward, a trigger on the barrel adapted to hold the plunger in a rear position in which the gun is loaded, an element pivotally mounted on the gun stock and associated with the plunger and adapted to draw the plunger rearward when the gun is bent at the junction of the gun stock and barrel, said barrel being formed with a longitudinal top opening, a pin on the plunger engaging in said opening and coactable with a pin projecting from a toy airplane to propel the 45 airplane as the plunger moves forward, and a pair of flanges on the sides of said opening forming tracks for guiding said airplane, said pair of flanges being pivotally mounted intermediate of their ends and adapted to assume various adjusted tilted positions for projecting the toy airplane at various desired angles, and clamp screws 50 for holding said flanges in fixed adjusted positions, said flanges having front sections pivotally connected with the main portions thereof, and means for holding said front sections in various 55 adjusted angular positions relative to said main sections. 60

4. A device of the class described, comprising a gun stock pivotally connected with a gun barrel, a plunger in the barrel, a spring urging said plunger forward, a trigger on the barrel adapted to hold the plunger in a rear position in which the gun is loaded, an element pivotally mounted on the gun stock and associated with the plunger and adapted to draw the plunger rearward when the gun is bent at the junction of the gun stock and barrel, said barrel being formed with a longitudinal top opening, a pin on the plunger engaging in said opening and coactable with a pin 70 projecting from a toy airplane to propel the airplane as the plunger moves forward, and a pair of flanges on the sides of said opening forming tracks for guiding said airplane, said pair of flanges being pivotally mounted intermediate 75

of their ends and adapted to assume various adjusted tilted positions for projecting the toy airplane at various desired angles, and clamp screws for holding said flanges in fixed adjusted positions, said flanges having front sections pivotally connected with the main portions thereof,

and means for holding said front sections in various adjusted angular positions relative to said main sections, and clamp screws for holding said front sections in desired positions.
